ROTARY PRINTING PRESS

George J. Prager, Bayshore, N. Y., assignor, by
mesne assignments, to The Printcote Co., Inc.,
New York, N. Y., a corporation of New York

Application November 25, 1936, Serial No. 112,690

5 Claims. (Cl. 101—154)

This invention relates to new and useful improvements in a rotary printing press.

The invention proposes the use of an intaglio operated roller to apply inks, such as oils, water colors, Rotogravure, anilines, lacquers, varnishes, pyroxilyn, bronzes, micas, various adhesives and other existing colors and materials to the printing roller or printing plate or printing element of a rotary surface printing machine.

According to this invention the particular type of intaglio roller is no limitation. It may be engraved with various designs, screens or patterns; it may be a pad screen finish; it may be a half-tone finish and other known finishes. The printing roller is also not limited to any specific design or construction and may be molded, hand cut, fixed or loose on a printing drum.

No claim is made to have invented a new intaglio printing system, but this invention does claim the use of the intaglio method to apply the inks, etc., to the printing cylinder, printing plate, printing blanket, or other printing element, and upon the printing surfaces of relief printing, in a rotary printing machine.

It is pointed out that this invention basically differs from intaglio printing in that the intaglio roller does not come in contact with the material to be printed; but merely is utilized to supply ink, color, or coating materials to the printing element, which in turn comes into contact with the material to be printed.

The instant invention is also distinct from offset printing in which the inked printing form is transferred to a smooth blanket (not engraved) and then the complete inked form transferred to the material to be printed. With offset printing an intricate and complicated timing mechanism is required. According to the instant invention, as previously pointed out, the intaglio roller merely supplies ink to the printing element and does not itself contribute to the actual printed form as it appears on the finished printed material.

The invention also proposes a method and construction which permits the printing of especially long units of a design or printed material which may then be repeated any number of times. Heretofore it was customary to fixedly attach a printing element on a printing drum and the length of the element was limited to the circumference of the drum. This invention proposes the provision of a loose printing element which engages over the drum and which hangs down and therefore may be of any length. For example, with a printing drum of 12", which here-

tofore would limit the length of a printed unit to approximately 36", with the instant invention it is possible to use a 12" drum to print units of say, 40' or 80', etc., without limitation, and only limited by market demands.

An important advantage gained by this invention in applying the inks, etc., by an intaglio roller to the printing element is that then a pre-determined amount of color or material may be applied to the printing surface. Heretofore, by the use of transferring rollers the ink which was applied to the printing element was but poorly controlled. Provision was made to adjust the pressures between the transferring rollers, but there was poor control. By using an intaglio roller which has its ink controlled by a blade, the control of ink to the printing element is definite.

Another and very important advantage of this invention is that a much cleaner printing job is produced. The reason for this is that the inks, etc., may be supplied in correct quantities. Heretofore it was customary to supply more ink than was actually needed and for this reason the finished printed form had a backwash; that is, at the point where the printing form or element left the material being printed there was an extra deposit of ink which could easily be seen even upon casual inspection of the printed material.

Another very important advantage gained by this invention is the economical application of solid coating of color with colors and material heretofore difficult to handle in producing solid effects. The reason for this advantage is the better control of the ink, etc. supplied to the printing element.

Another advantage of this invention resides in the fact that the setup may be done much more quickly than heretofore.

Another object of the invention is the construction of a device as described which is simple and durable and which may be manufactured and sold at a reasonable cost.

For further comprehension of the invention, and of the objects and advantages thereof, reference will be had to the following description and accompanying drawing, and to the appended claims, in which the various novel features of the invention are more particularly set forth.

In the accompanying drawing forming a material part of this disclosure:

Fig. 1 is a fragmentary side elevational view of a rotary printing press embodying this invention.

Fig. 1a is a fragmentary side elevational view

similar to a portion of Fig. 1 but illustrating another embodiment of the rotary printing press.

Fig. 2 is a fragmentary view of the intaglio roller illustrated with a magnifying glass thereon 5 to clearly show the engraved or other design thereon.

Fig. 3 is a fragmentary elevational view of a piece of printed material.

Fig. 4 is a schematic view of another arrangement of a rotary printing press embodying this invention.

The rotary printing press, according to this invention, comprises a frame 10 upon which a printing drum 11 is rotatively supported and 15 which in turn supports a printing element 12. The particular printing element shown on the drawing is an endless blanket. The lower portion of this blanket is shown supported on a guide roller 13 which is mounted in an adjustable bearing 14 supported on the vertical members 15 of 20 the frame of the printing press. It is possible to substitute printing blankets 12 of various lengths for the one shown on the drawing. In the embodiment of the invention shown in Fig. 1a a different blanket has been substituted in the machine to indicate that blankets of various lengths 25 may be used. In this figure, the blanket indicated by reference numeral 12a, is much longer than the blanket 12. The bearing 14' has been 30 shifted to a new position, a lowered position with respect to that shown in Fig. 1, to cooperate with the long blanket 12a. In other respects this embodiment is identical to that shown in Fig. 1, and the identical parts may be identified by similar 35 reference numerals.

A pressure drum 16 is adjustably mounted on the printing frame 10 and is cooperative with the printing drum 11 and the printing element 12 to supply the necessary pressure to print a web 40 of paper 17 passing between these parts. The ink or similar material is supplied to the printing element 12 by an intaglio roller 18. This intaglio roller has a conventional intaglio blade 19 cooperative therewith. The intaglio roller 18 is 45 shown in contact with a furnishing roller 20 which engages into an ink pan 21. Any number of furnishing rollers may be interposed between the ink pan and the intaglio roller 18, or the intaglio roller may be engaged directly into the ink pan.

The intaglio roller 18 is mounted upon a bracket 22 which is slidably mounted in a standard 50 23 mounted on the frame 10 of the printing machine. The bracket 22 is controlled by a screw 24, by which the pressure between the intaglio roller 18 and the printing element 12 55 may be adjusted. The furnishing roller 20 is mounted in a bracket 25 which is slidably supported and controlled by a screw 26. A conventional handle control eccentric 27, not shown in detail on the drawing, is provided for moving the intaglio roller 18 out of contact with the printing element 12 without disturbing the adjustment of the screw 24.

The pressure drum 16 is slidably mounted in a 60 standard 28 and is controlled by a screw 29. There is also a handle controlled eccentric 30, not shown in detail, for moving the pressure drum 16 out of contact with the printing element 12 without disturbing the adjustment of the screw 29.

The details of the eccentric controlled handles 27 and 30 and the details of the brackets which are moved by the screws for pressure control, etc., will not be given in this specification as they 70 form no part of this invention and similar con-

structions are known. In this respect attention is called to the application of George Prager, Serial No. 97,859, filed on August 25, 1936.

Fig. 2 illustrates an enlarged detailed view of the intaglio roller 18. A magnifying glass 31 is 15 shown engaged over the roller 18 to make clear the design thereon. Numeral 32 indicates the design which may be an engraved or hand cut screen or pattern design, etc., as before mentioned. The intaglio blade 19 is of conventional 20 construction and shown provided with a counter-weight 33 adjustable on a radial arm 34 connected with the intaglio blade by which the pressure of the intaglio blade against the intaglio roller may be controlled.

Other details of the printing press will not be given in this application since they form no part of this invention and since prior constructions are generally known. For example, the means for driving the various rollers are not shown.

The operation of the device is as follows:

The intaglio roller 18 receives its ink or similar material from the furnishing roller 20 which works in the ink pan 21. The intaglio blade 19 25 cleans all excess ink from the intaglio roller 18, if properly adjusted. The amount of ink left depends entirely on the depth of the intaglio engraving. If it is desired that the intaglio roller transfer a large quantity of ink, a suitable design of greater depth capable of retaining a larger 30 quantity of ink should be used. To transfer a small quantity of ink, a fine design should be used. The intaglio roller then lays the ink upon the printing element 12.

The printing ink on the printing element will 35 be in small dots or other designs engraved upon the intaglio roller. Thus, the printing surfaces of the printing element 12 are supplied with a finely controlled supply of ink. The printing element 12 then operates to transfer its printed 40 form upon the web 17. Attention is called to the fact that the design from the intaglio roller 18 will not be transferred to the web 17 since the printing ink will be squashed during the transfer to the printing element 12. Of course, the engraved or other printed form on the printing element 12 will be printed on the web 17.

Fig. 3 shows a sheet of material 34 which is 50 printed with a solid color 35 indicated by cross hatching, and several letters 36 are printed in reverse. In the old methods of printing there will be a back lash of ink (shown by a heavy line on the drawing) along the tops of the letters 36, these tops being indicated by the letters a. There will also be a back lash along the area b and also 55 a back lash along the area c, all shown by heavy lines. This back lash is formed by too much ink being on the printing element and this ink being squashed out along the edges of the printing element under pressure required for printing. Then 60 a well of excess ink is deposited at all engraved areas. With the instant invention this back lash is eliminated due to the fact that only as much ink as the material will consume in this operation is applied.

In Fig. 4 a schematic view of another printing press constructed according to this invention has been disclosed merely to illustrate that different forms of printing presses may embody the same invention. In Fig. 4 the printing drum is indicated by reference numeral 11'. Over this drum the printing element or blanket 12' extends. This printing element 12' is endless and has a portion depending downwards, which portion is guided over a drum 13'. A pressure drum 16' coacts with 70 75

the printing drum and printing element. A web of paper 17' passes between the pressure drum and the printing element. An intaglio roller 18' engages against the printing element 12' at an area where the printing element is forced against the printing drum 11'. This intaglio roller 18' has a cooperating intaglio blade 19'. The intaglio roller 18' is shown disposed directly in an ink pan 21'.

10 The operation of the device shown in Fig. 4 is identical to the prior form. The intaglio roller 18' will print upon the printing element 12' which is loose upon the printing drum 11' so that it may be of any desired length and not controlled 15 by the diameter of the printing drum. The inked printing element 12 will print on the web 17'.

While I have illustrated and described my invention with some degree of particularity, I realize 20 that in practice various alterations therein may be made. I therefore reserve the right and privilege of changing the form of the details of construction or otherwise altering the arrangement of the correlated parts without departing from 25 the spirit or the scope of the appended claims.

Having thus described my invention, what I claim as new and desire to secure by United States Letters Patent is:

1. In a rotary printing press, a frame, a form 30 supporting roller mounted on said frame, a flexible form element engaging over said roller and having its bottom portion loosely and freely depending, a pressure drum adjustably mounted on said frame and cooperative with the top portion 35 of said flexible form element, and an intaglio roller adjustably mounted on said frame and cooperative with the side portion of said flexible form element which is adjacent said form supporting roller.
- 40 2. In a rotary printing press, a frame, a form supporting roller mounted on said frame, a flexible form element engaging over said roller and having its bottom portion loosely and freely depending, a pressure drum adjustably mounted on

said frame and cooperative with the top portion of said flexible form element, an intaglio roller adjustably mounted on said frame and cooperative with the side portion of said flexible form element which is adjacent said form supporting roller, vertical track members on said frame, bearings adjustably mounted on said track members, and a guide roller supported by said bearings and engaging through the lower portion of said flexible form element for guiding same. 10

3. In a rotary printing press, a frame, a form supporting roller mounted on said frame, a flexible form element engaging over said roller and having its bottom portion loosely and freely depending, a pressure drum adjustably mounted on 15 said frame and cooperative with the top portion of said flexible form element, an intaglio roller adjustably mounted on said frame and cooperative with the side portion of said flexible form element which is adjacent said form supporting roller, 20 vertical track members on said frame, bearings adjustably mounted on said track members, and a guide roller supported by said bearings and engaging through the lower portion of said flexible form element for guiding same, said track members being located adjacent to the ends of said form supporting roller so that said flexible form element may extend down between said track members. 25

4. In a rotary printing press, a frame, a form 30 supporting roller mounted on said frame, and a flexible form element engaging over said roller and having its bottom portion loosely and freely depending.

5. In a rotary printing press, a frame, a form 35 supporting roller mounted on said frame, and a flexible form element engaging over said roller and having its bottom portion loosely and freely depending, and a pressure drum adjustably mounted on said frame and cooperative with the 40 top portion of said flexible form element so as to engage against a portion rested on said form supporting roller.

GEORGE J. PRAGER.
